UNITED STATES PATENT OFFICE

105,560

DESIGN FOR A COAT

Morris Spector, New York, N. Y.

Application June 26, 1937, Serial No. 70,076

Term of patent 3½ years

To all whom it may concern:

Be it known that I, Morris Spector, a citizen of the United States of America, residing in the city of New York, county of New York, and State of New York, have invented a new, original, and ornamental Design for a Coat, of which the following is a specification, reference being had to the accompanying drawing, forming part thereof.

Fig. 1 is a front perspective view of a coat showing my new design.

Fig. 2 is a rear view thereof.

Fig. 3 is an enlarged view of the sleeve as shown in Fig. 1.

The characteristic feature of my design resides in the combination on the instant coat of the sleeve members draped as shown.

I claim:

The ornamental design for a coat substantially as shown and described.

MORRIS SPECTOR.
